United States Patent Office.

GEORGE NIMMO, OF JERSEY CITY, NEW JERSEY.

Letters Patent No. 65,110, dated May 28, 1867.

IMPROVEMENT IN FURNACES FOR HEATING AND WELDING.

The Schedule referred to in these Letters Patent and making part of the same.

TO ALL WHOM IT MAY CONCERN:

Be it known that I, GEORGE NIMMO, of Jersey City, in the county of Hudson, and State of New Jersey, have invented and made a certain new and useful Improvement in Furnaces for Heating and Welding; and I do hereby declare the following to be a full, clear, and exact description of the same, reference being had to the annexed drawing, making part of this specification, wherein—

Figure 1 is an elevation of said furnace.

Figure 2 is a longitudinal section; and

Figure 3 is a plan of the same sectionally, at the line *x x* of fig. 1.

Similar marks of reference denote the same parts.

Furnaces for heating and welding by the same fire have been constructed before, as may be seen by reference to Letters Patent granted to G. Nimmo and R. S. Stanton, June 14, 1864. In this, however, a separate chamber is provided, adjacent to the fire, for heating the metal to a welding heat, and another one, further off, for heating purposes. I have constructed my furnace with a view to economizing heat, by bringing the heating-chamber nearer to the fire, and providing an opening or openings into the furnace at the end of the fire-chamber, so as to employ the direct action of the fire upon the articles to be welded, which are introduced upon or within the incandescent fuel.

In the drawing, *a* is the fire-chamber, and *b* the heating-chamber; *e* is the escape flue to a chimney of any desired character. The walls of the furnace are properly built and sustained with plates and buckstaves with tie-bolts, and the hearth and crown, as well as the entire interior portions, are lined with fire-brick. The end wall of the furnace is provided with an opening, *d*, for the introduction of fuel, and the side wall has the openings *e e*, to give access to the heating-chamber *b*, and to these, slides or doors are to be provided. I form an opening in the wall at the end of the furnace, as at *f*, through which articles to be welded are inserted amongst the incandescent fuel, or over the same. By this construction the fuel is economized, because the articles to be welded, coming into contact with the fuel, are heated much more rapidly than they would be by the flame alone, and the articles to be heated, for rolling or otherwise working, which are placed on the hearth of the chamber *b*, are more rapidly heated, because they are much nearer the fire. The tuyere *h*, supplying air to the fire, is introduced through the end wall; and the cinders and refuse from the fuel are removed, when necessary, through a hole made in the brick-work. A door may be put in the end wall, at the opposite end of the heating-chamber to the fire, if desired, so as to give greater access to that heating-chamber, for allowing the introduction of longer articles.

What I claim, and desire to secure by Letters Patent, is—

The welding and heating-furnace, formed with the heating-chamber *b*, fire and welding-chamber *a*, and openings *d*, *e e*, and *f*, in the manner and for the purposes set forth.

In witness whereof I have hereunto set my signature this 18th day of October, A. D. 1866.

GEORGE NIMMO.
